UNITED STATES PATENT OFFICE.

ISABELLA COHEN, OF NEW YORK, N. Y.

BANK-NOTE TESTER.

935,963.

Specification of Letters Patent.

Patented Oct. 5, 1909.

Application filed February 18, 1909. Serial No. 478,703.

To all whom it may concern:

Be it known that I, ISABELLA COHEN, a citizen of the Empire of Austria-Hungary, residing in New York, in the borough of 5 Manhattan, county and State of New York, have invented certain new and useful Improvements in Bank-Note Testers, of which the following is a specification.

This invention relates to an improved 10 tester or apparatus for testing the genuineness of bank-notes, said apparatus being intended to be used by banks and other institutions for quickly distinguishing a forged or spurious bank-note from a genuine one; 15 and for this purpose the invention consists of a bank-note tester which comprises a supporting-bar provided with a handle, a magnifying-lens, swiveled to the front-end of said bar, a movable stand adapted to slide 20 on the supporting-bar, and means on said stand for holding the genuine and the spurious bank-notes side by side so as to compare them by looking through the magnifying-lens.

25 The invention consists further of certain details of construction which will be fully described hereinafter and finally pointed out in the claims.

In the accompanying drawings, Figure 1. 30 represents a perspective view of my improved bank-note tester, Fig. 2 is a front-elevation of the supporting-stand for supporting a genuine and a spurious bank-note side-by-side, said figure being drawn on a larger scale, Fig. 3 is a vertical transverse section on line 3, 3, Fig. 2, and Fig. 4 is a detail vertical section of the swivel-connection of the magnifying-lens with the supporting-bar of the device.

40 Similar letters of reference indicate corresponding parts throughout the several figures.

Referring to the drawings, *a* represents the supporting-bar of the improved bank-note-tester, which bar is provided with a handle *h* at the under-side. To the front-end of the supporting-bar *a* is applied a magnifying-lens *l*, which is surrounded by a ring-shaped frame *l*¹ and swiveled by a post *l*² on said 45 frame to a socket *l*³ attached to the supporting-bar *a*. The swivel-connection of the magnifying-lens *l* with the supporting-bar *a* permits the lens to be turned on the axis of its post, as required, in looking at special 50 portions of the bank-notes to be examined.

On the rear-portion of the supporting-bar

a is guided a transverse frame or stand *b* on which a genuine and spurious bank-note can be placed side-by-side, said stand being guided by a recess *b*¹ of its base-rail *b*² on the supporting-bar *a* and held thereon by a spring-actuated friction-device *b*³, having a handle *b*⁴, as shown in Fig. 3. The supporting-frame or stand *b* is formed of two parts *b*^x which are connected by the base-rail *b*², and a grooved rail *d* on which the bank-notes can be supported side-by-side, the genuine one preferably on the left-hand and the spurious one on the right-hand side, or vice versa. Each part *b*^x is provided with 60 a button or knob *i* at its lower end for moving the stand *b* conveniently forward or backward on the rail *a*. The lower edges of the bank-notes rest in the groove of the transverse rail *d*, and against the two stands 65 and are held at the upper edges by hooks *e*, said hooks being connected by means of two pivot-links *e*¹ with the upper ends of spring-actuated arms *e*² which are bent into spring-coils at the lower part and attached to a 70 cross-bar of the stand. The hooks *e* yield 75 by their spring-connection with the stand sufficiently to engage the upper edges of the bank-notes, as indicated in dotted lines in Fig. 2. Midway between the stands is arranged a separating device *f*, which is made 80 in the shape of a wire loop having a pointed end, which latter is inserted into a hole at the center of the base-rail. The separating device serves as an abutment for the ends 85 of the bank-notes but keeps them separated 90 from each other at their meeting edges.

For examining a spurious bank-note it is placed in position on one stand, with its lower edge inserted into the grooved rail of 95 the same and the inner edge placed against the separating device *f*. The upper edge is then placed in engagement with the yielding hook *e*. The genuine bank-note is then placed side-by-side with the spurious one on 100 the second stand and held thereon by the yielding hook, in the same manner as the spurious bank-note. The bank-notes are then compared by means of the magnifying-lens, which is turned on its swivel-connection with the supporting-bar in the direction of one bank-note and then in the direction of the other, so that the differences in 105 the bank-notes can be readily detected and the spurious or forged bank-notes readily 110 detected.

The device forms a convenient means for

detecting forged bank-notes to be used by banks, moneyed institutions, and wholesale business-concerns in which a large number of bank-notes are handled.

5 Having thus described my invention, I claim as new and desire to secure by Letters Patent:

1. In a bank-note tester, a bank-note supporting frame comprising a base-rail, two 10 separate upright stands on the same, a grooved rail connecting said stands for supporting the lower edges of the bank-notes, and yielding hooks for engaging over the upper edges of the bank-notes.
- 15 2. In a bank-note tester, a bank-note supporting frame comprising a base-rail, two separate upright stands on the same, a grooved rail connecting said stands for supporting the lower edges of the bank-notes, 20 yielding hooks for engaging over the upper

edges of the bank-notes, and a separating device located midway between the stands.

3. In a bank-note tester, a bank-note supporting frame comprising a base-rail, two separate upright stands on the same, a 25 grooved rail connecting said stands and spaced above said base-rail spring pressed arms secured to the stands, links connecting the free ends of the arms, hooks secured to the links for engaging over the upper edge 30 of a bank-note, and a separating device located on the base-rail and extending above the grooved rail midway between the stands.

In testimony, that I claim the foregoing as my invention, I have signed my name in 35 presence of two subscribing witnesses.

ISABELLA COHEN.
